UNITED STATES PATENT OFFICE.

HERBERT WILLIAM HUNT AND PERCY HUNT, OF OLD TRAFFORD, MANCHESTER,
ENGLAND.

TWIST-DRILL-POINT GRINDING AND THINNING MACHINE.

Application filed February 10, 1927, Serial No. 167,324, and in Great Britain December 21, 1926.

This invention refers to twist drill point grinding and thinning machines.

The object of the improvements is to provide improved facilities for grinding out the flutes of the drill next the drill point and thus maintaining the thickness (or thinness) of such point with each sharpening of the drill.

In our prior Patent No. 1,448,746, a small grinding wheel is provided for a like purpose, but the drill has to be fixed in one holder for grinding the cutting edges and in another and separate holder for grinding the flutes, furthermore, the drill requires to be carefully set for each operation.

According to this invention, a small grinding wheel is mounted so that the grinding out of the flutes, or thinning the point, can be effected whilst the drill is still in the holder for grinding the cutting edges, thus avoiding transference from one holder to another and also avoiding the need for resetting.

The invention will be described in detail with the aid of the accompanying drawings, wherein:

Fig. 1 is a side elevation, and

Fig. 2 a plan view of so much of a twist drill grinding machine as is necessary to illustrate the invention.

Fig. 3 is a plan of the point of a drill and of the small grinding wheel used to grind the flutes.

Figs. 4 and 5 are side elevation and plan respectively to a larger scale, of a part of the machine shown in Fig. 1, and Figs. 6 and 7 are views of detail parts hereinafter described.

In Figs. 1 and 2, *a* is a tray on which the main parts of the machine are mounted, the tray in turn being supported by a box casting or pedestal *b*. Journaled in bearing *c* is the shaft *d* to which is keyed the clamp for detachably securing the main grinding wheel *e* to said shaft, a guard *f* enclosing the major portion of the wheel. To the end of the shaft *d* is secured a disc *g* provided with a facing of leather or like yielding and frictional material *g*¹. Rising from the tray *a* is a bracket *h* (see Fig. 6) from which extends a boss *i*. Rotatably mounted in the boss is a stem or shank part *j* of a T-shaped bearing member *k*. Mounted in said member is a hollow shaft *k*¹ held to the bearing

by closing the split end therein by a nut *k*². 55 Journaled in said shaft is a spindle *l*. Keyed to said spindle is a metal collar *m* which under the pressure of a spring *n* between the boss *i* and bearing *k* normally contacts with the facing *g*¹ on the disc *g* and transmits the motion of the disc to the spindle *l*. Detachably secured to the forward end of the spindle is a flute grinding wheel *o*, the upper parts of the wheel being covered by a guard *p*. In one with the bearing member *k* is a lateral extension *k*³ (see Fig. 7) through which passes a screw *k*⁴, the point of which is adapted to contact with a shoulder on the bracket *h* and limit the downward angular movement of the 70 wheel *o*. A spring *q* may be provided to hold the wheel *o* raised when not in use.

Upon the front end of the boss *i* are cam faces *r*, *r* and to the end of the shank *j* is fitted a pin *j*¹ which bears against the boss under the pressure of the spring *n*. When the wheel *o* is raised the shank *j* is rotated and its pin *j*¹ caused to ride up the cam faces *r*, *r* and thereby draw the collar *m* clear of the disc *g*, and stop rotation of the 80 wheel *o*. Contrawise, on the wheel being lowered, the pin moves down the cam faces and allows the collar *m* to engage the disc and start the wheel *o* rotating.

The twist drill to be ground and pointed 85 is mounted in the usual holder carried upon a plate *t* pivotally movable about a stud *u* supported upon a slide or carriage *v*. This latter is adapted to move to and fro on guides *v*¹ and with the drill properly positioned in the holder to move one of the cutting edges of the drill across the periphery of the grinding wheel *e* in the usual way.

After the cutting edges of the drill point have been sharpened, the carriage *v* is moved 95 to a position opposite the flute grinding wheel *o*, when such wheel is brought down by hand to the angular position shown in Fig. 1, when its edge contacts with the surface of the drill flute and grinds away a portion of the metal lying next to the point and alongside one of the cutting edges, see Fig. 3. The drill is then given a half turn in its holder, and the grinding wheel *o* is again brought down and caused to grind away a 100 portion of the metal lying next to the point and alongside the other cutting edge of the drill, thereby thinning the point of the drill 105

as well as imparting a slight undercut to the cutting edges.

To assist in quickly determining the correct position of the drill after a half rotation, the collar α may have diametrically opposite notches with which a lever y may engage when pressed down by hand, the lever being at other times held clear of the collar by a spring.

10 The movements of the carriage v may be conveniently effected by a hand lever w pivoted to the tray a and at the end of its shorter arm engaging a slot in the underside of the carriage.

15 In the case of automatically controlled machines, the carriage will be moved by hand after disengaging it from its operating mechanism, or by the rack and pinion described in our prior Patent No. 1,448,746.

20 What we claim is:—

1. In twist drill point grinding machines of the kind comprising a main grinding wheel, for grinding the cutting edges of the drill, a drill-holder, a support for the drill-holder and a slidably mounted carriage on which the drill-holder support is pivoted, the combination therewith of a further but smaller grinding wheel, means for rotatably supporting the smaller wheel alongside the main grinding wheel, means for transmitting the motion of the main grinding wheel shaft to the smaller grinding wheel, and means for positioning the smaller grinding wheel at an angle to the vertical and with its lower part 35 at a point where on said carriage on which the drill-holder support is mounted being moved in a direction parallel with the axis of the main grinding wheel, a portion of the drill next the drill point and next to one of the cutting edges is removed and the cross

section of the drill at such parts thinned, as set forth.

2. In twist drill point grinding machines and in means for removing portions of the drill next the drill point and next to one of the cutting edges as claimed in claim 1, a T-shaped member with hollow head part and solid stem part, a fixed bracket in which the solid stem part is slidably and rotatably journaled, a hollow and non-rotary shaft in said hollow head part of the T-shaped member, a spindle rotatably mounted in said hollow shaft, a grinding wheel secured to one end of said spindle, and a driving collar secured to its other end, a friction disc on the end of the main grinding wheel shaft, with the side face of which the periphery of the said collar may frictionally contact, a spring for pressing the collar against the disc, and a cross pin and cam faces between the stem 60 of the T-shaped member and the fixed bracket whereby on the T-shaped member being given an angular movement in one direction, the collar is caused to leave the disc and stop the rotations of the smaller grinding wheel, while when given an angular movement in an opposite direction, the collar is allowed to engage the disc and start the rotations of the smaller grinding wheel, regulatable means being provided between 65 the fixed bracket and the T-shaped member for limiting the angular movements of the latter in one direction and determining the position of the grinding wheel when required to operate upon the drill point, as set forth. 70 75

In testimony whereof we have signed our names to this specification.

HERBERT Wm. HUNT.
PERCY HUNT.
